UNITED STATES PATENT OFFICE.

WILLIAM J. COULTER, OF LORAIN, OHIO.

TICKET COUNTING AND CANCELING MACHINE.

No. 821,465.

Specification of Letters Patent.

Patented May 22, 1906.

Application filed July 17, 1905. Serial No. 269,996.

To all whom it may concern:

Be it known that I, WILLIAM J. COULTER, a citizen of the United States, and a resident of Lorain, in the county of Lorain and State of Ohio, have made a certain new and useful Invention in Ticket Counting and Canceling Machines; and I declare the following to be a full, clear, and exact description of the same, such as will enable others skilled in the art to which it appertains to make and use the invention, reference being had to the accompanying drawings, and to characters of reference marked thereon, which form a part of this specification.

15 My invention relates to machines for counting street-railway and other tickets of various sizes and thickness and similar matter of all kinds, and it further relates to machines for counting and canceling such tickets.

20 It has for its object chiefly to provide a means for mechanically counting such tickets with speed and accuracy and in connection therewith means for at the same time effectually destroying them; and it consists 25 in the novel construction and combinations of elements and devices hereinafter set forth.

In the accompanying drawings, illustrating a machine embodying my invention, Figure 1 is a plan view, partly broken away.

30 Fig. 2 is a vertical sectional view with parts removed. Fig. 3 is a side elevation with parts in dotted lines, and Fig. 4 is a front elevation.

In the drawings the numeral 1 represents 35 tickets to be counted. These tickets are held packed facewise together in upright position and on edge in a longitudinal feedway *g* by a feeding-slide 2, which has a projection which runs in a slot in the table 3 and to 40 which is bolted on the under side a plate 4, which holds the same in place. The feeding-slide 2 is moved forward by means of a steel band 5, bolted to the plate 4 at one end and having its other end attached to a drum 6, in 45 which is confined a spring 7, designed to give the same forward rotary movement. By means of these devices the tickets are moved forward facewise and made to engage fingers 8, which are secured to the framework in 50 front of the feed and serve to hold them at the proper angle to insure their being taken off readily by a transposing-roller 9, into which is set in peripheral recesses *a* at regular inter-

vals friction-plates 10 of tempered steel, which are held in place by screws 11, each 55 plate having a rasp-like face adapted to engage a ticket facewise and carry it around edgewise as the roller turns on its journals.

The separating and transposing roller 9 is made to fit into its semicylindrical seat *b* in 60 the table 3 with such exactness that a ticket cannot pass between their surfaces, but must wait until engaged by one of the plates 10, which are made each with its curved friction-face depressed in its recess just enough to 65 allow one ticket to pass down edgewise between it and the surface of the seat *b* with slight friction.

Journaled in bearings of the frame below the seat *b* is a shaft 13, which carries sprocket-wheels 12, having spurs *c*, which extend through slots of said seat and into grooves of the roller 9. Each ticket carried by the roller 9 engages the sprocket-wheels and turns them sufficiently to allow it to pass 75 through. In this manner the tickets are counted automatically by the sprocket-wheels, which by means of their shaft 13, gears 14 and 14^a, shaft 15, and pinion 16 communicate their action to the registering-dials 17 and 17^a and cause the dial 17 to move one space for each ticket.

The registering-dial 17 has one hundred teeth and is graduated to resemble the face of a watch with the Roman figures. This dial 85 has underneath it, incased in a drum, a spring 18, which is connected to the center post 19, but allowed to remain free at the outer end. Sufficient tension is provided thereby to throw the dial 17 back to "0" when released 90 by movement of a lever 20, to which it is secured, and at the same time this tension will not allow the spring to become completely wound up. To prevent the action of this spring from causing the dial to return to "0" 95 when the machine is in operation, a ratchet-wheel 21 is placed on the shaft No. 13 and a pawl 22, held in place by spring 23, is pivoted to an arm of the frame to engage said ratchet-wheel.

When the dial 17 has registered "100," a pin 24 thereon engages a pawl 25 and is allowed to pass, and at the same time a pin 26 of said dial engages the dial 17^a and turns it one point. The dial 17^a has ten figures and is 105 provided with a ratchet-wheel 28 to engage

a pawl 27 on the lever 20, which is designed to prevent the dial from running back to "0." When the lever 20, which is pivoted to the frame at 44 and is held in place by spring 29, 5 is moved to the right, the dial 17, carried by the lever 20, is released from the pinion 16 and the pawl 27 from the ratchet 28, and both dials are turned back to "0" instantly, the pin 24 striking the pawl 25 and stopping 10 and the dial 17^a operating in a similar manner.

Each ticket after passing the counting sprocket-wheels 12 is carried by the transposing-roller until it engages the guide-fingers 30, attached to the frame, which divert it 15 from the roller and carry it between the canceling-rollers 31 and 31^a. These canceling-rollers are made from tempered steel and serve to punch rows of holes in each ticket, which by means of engaging fingers 32 is 20 afterward removed from the machine.

The canceling-rollers 31 and 31^a are mutually operated by gear-wheels 33 and 33^a and driven by a gear-wheel 34, which in turn is driven by a gear 35 and the latter by a hand 25 or power wheel at 36.

The indicator-hand 37, which extends from the center of the units-dial toward the hundreds-dial at all times points to the number of tickets counted, the dial 17 showing 30 units and the dial 17^a hundreds.

The table 3 is secured to frame 38 by means of bolts 39, and the frame is further held in position by means of a separator-brace 40, which is secured in place by bolts 41. 35 The registering-dial 17 and lever 20 are connected with the top plate 42 of the frame by means of a pivot-bolt 43, and the top plate is secured in place by means of bolts 44.

My invention permits of many modifications, the broad idea being to provide a mechanical counting and canceling device for automatically accomplishing the ends referred to. It may be varied in form and proportions, depending largely on the size of tickets 45 to be counted.

In the operation of this machine the tickets are packed with their faces together and are placed in the feedway *g*, where they are pushed forward by the feeding-head to the 50 end of the feedway, where they are separated one by one from the end of the pack by the transposing-roller, which carries them in edgewise succession and causes them to engage one by one the sprockets or projections 55 of a rotary shaft, whereby they are counted, the counting being registered on suitable dials, which are in engagement through suitable gearing with said rotary shaft. After each 60 ticket has passed the counting-sprockets it is pushed edgewise between punching-rolls, whereby it is canceled, and it is then by means of a clearing device thrown out of the machine counted and canceled.

Difference in thickness of tickets is de-

signed to be compensated for by introducing 65 thin metallic liner-plates under the friction-blocks, whereby the latter are adjusted to proper position.

Having described my invention, what I claim is—

1. In a counting and canceling machine, the combination of a spring-propelled automatic feeding device, a metallic friction-roller, a reversing register, a canceling device and means for operating the same, substantially as specified.

2. In a ticket-counting machine, the combination with a facewise feed, of a separating and transposing carrier, and means adapted to be automatically operated by the tickets 80 in engagement with said carrier, to count said tickets and register the count, substantially as specified.

3. A ticket-counting machine having in combination with a facewise feed, means for 85 separating the tickets and transposing them from facewise to edgewise succession, and ticket-operated means for count-registering devices, substantially as specified.

4. A ticket-counting machine having in 90 combination with a facewise feed, rotary frictional means for separating the tickets and transposing them from facewise to edgewise succession, and means for positively moving such tickets in edgewise succession to operate the counting and registering devices, substantially as specified.

5. In a ticket-counting machine, the combination with the feed, of a recessed transposing and separating roller and a seat in 100 close apposition to said roller whereby the feed is changed from facewise to regular edgewise progression, substantially as specified.

6. In a ticket-counting machine, the combination with a facewise feed, and rotary 105 frictional means for transposing and separating the tickets and carrying them in regular edgewise succession, of means for counting and registering said tickets, substantially as specified.

7. In a ticket-counting machine, a transposing-roller having recesses at regular intervals in its periphery, and friction-plates depressed in said recesses, substantially as specified.

8. In a ticket-counting machine, the combination with a longitudinal feedway and means for feeding the tickets facewise thereon, of a semicylindrical seat at the end of said feedway, a recessed transposing-roller 120 in close apposition to said seat, and depressed friction-plates in said roller, substantially as specified.

9. In a ticket-counting machine, the combination with an automatic feed of a transposing and separating friction-roller, its slotted seat, ticket-operated sprocket-wheels, their shaft, and count-registering devices in

gear with said shaft, substantially as specified.

10. A ticket-counting machine, having a facewise feed, a transposing and separating carrying-roller, a slotted seat therefor, ticket-operated sprocket-wheels, their shaft, count-registering devices and gearing connecting the latter with said shaft, substantially as specified.

11. In a ticket-counting machine, the combination with a facewise feed, and count-registering devices, of a transposing and separating ticket-carrier, a slotted seat therefor, ticket-operated counting devices, and gearing connecting said counting devices and count-registering devices, substantially as specified.

12. In a ticket-counting machine, the combination with a feedway, terminating in a semicylindrical slotted seat, spring-actuated feeding devices, a transposing and separating carrying-roller, ticket-operated sprocket-wheels, their shaft, adjustable registering-dials, gearing in connection with said shaft and dials, an adjusting-lever, and means for resetting the dials, substantially as specified.

13. In a ticket counting and canceling machine, the combination with an automatic feed, count-registering devices and canceling-rolls, of a transposing and separating roller, its slotted seat, ticket-operated counting-wheels in gear with said count-registering devices, ticket-guiding fingers, and ticket-clearing fingers, substantially as specified.

14. In a machine of the class described, a separating and transposing carrier, ticket-counting means in the path of the tickets on

the carrier, and ticket-canceling means, substantially as specified.

15. In a machine of the class described, a separating and transposing carrier having engagement with means for holding the tickets against movement, and ticket-counting means having a toothed wheel in the path of the tickets on the carrier, substantially as specified.

16. In a machine of the class described, means for separating and transposing the tickets in succession, means for holding the tickets against movement with relation to the separating and transposing means while in transit, and ticket-counting means in the path of the tickets, substantially as specified.

17. In a machine of the class described, a feeding means, means for separating and transposing the tickets in succession, means for holding the tickets against movement with relation to the separating and transposing means while in transit, and ticket-counting means in the path of the tickets, substantially as specified.

18. In a ticket counting and canceling machine, the combination of ticket-feeding means, ticket-counting means, and ticket-canceling means including a grooved roller, and a toothed roller the teeth of which engage the grooves of the grooved roller, substantially as specified.

In testimony whereof I affix my signature in presence of two witnesses.
